US00D521777S

(12) **United States Design Patent** (10) **Patent No.:** **US D521,777 S**
(45) **Date of Patent:** **** May 30, 2006**

(54) **SURFACE SHELF**

(75) Inventors: **Michael L. Gusdorf**, St. Louis, MO (US); **Hsing-Ling Li**, Crawford, MO (US)

(73) Assignee: **Industrial Wire Products, Inc.**, Sullivan, MO (US)

(**) Term: **14 Years**

(21) Appl. No.: **29/221,739**

(22) Filed: **Jan. 20, 2005**

(51) **LOC (8) CL.** **06-06**

(52) **U.S. CL.** **D6/511**

(58) **Field of Classification Search** D6/491, D6/509-511, 402, 481, 500, 332; 108/27, 108/59; 211/59.2, 135, 153; 312/140.1, 140.4

See application file for complete search history.
